P. DULLAARDT.
COMBINED MOP AND WRINGER.
FILED AUG. 5, 1921.

Inventor:
Pieter Dullaardt
by Mrs H. Babcock, his attorney.

UNITED STATES PATENT OFFICE.

PIETER DULLAARDT, OF Utrecht, NETHERLANDS.

COMBINED MOP AND WRINGER.

Application filed August 5, 1921. Serial No. 490,061.

To all whom it may concern:

Be it known that I, PIETER DULLAARDT, merchant, a subject of the Queen of the Netherlands, residing at Utrecht, 25 Park-
5 straat, in the Kingdom of the Netherlands, have invented certain new and useful Im-
provements in Combined Mops and Wringer-
ers, of which the following is a specification.

The present invention relates to an appa-
10 ratus for cleaning floors by means of a mop
cloth of the type comprising a handle, a
socket adapted to receive one end of the
handle, a wringing device carried by the
handle, a plate pivotally connected to the
15 socket, a mop holding frame fixed to said
plate and a mop cloth connected to the
wringing device.

The object of the present invention is the
provision of an apparatus of this type,
20 wherein the mop cloth is connected to the
wringing device in such a manner that it
can easily be removed, and is held by the
frame only during the mopping operation,
so that the frame is not bent or distorted
25 otherwise by the wringing of the mop cloth.

A further object of the invention is to
provide a device of the character described
in which the mop cloth may hang down
freely from the wringing means or may be
30 connected to a bucket handle, during the
wringing operation.

The present invention consists of the con-
struction, combination and arrangement of
parts hereinafter fully described and
35 claimed.

Referring to the drawings, in which simi-
lar numerals indicate the same parts
throughout the several views, Figure 1 is a
side elevation of the apparatus constructed
40 in accordance with the invention, showing
the mop cloth in section. Figure 2 is a front
view of the hook, by which the mop cloth is
connected to the handle of a bucket. Fig-
ure 3 is a top plan view of the apparatus
45 after removing the mop cloth. Figure 4 is
a side view of a hook used instead of the
hook illustrated in Figure 2 and pivotally
mounted on the handle of a bucket.

The handle 1 is engaged in a ferrule or
50 tubular socket extension 2, the latter being
formed with spaced parallel ears 19 to which
is pivotally connected a plate 3, the same
being formed with upturned ears 17 through
which are passed pivots 18, the same being

also passed through the depending ears of 55
the ferrule or socket extension.

Fixed to the plate 3 is a mopholder com-
prising a frame 4, the latter being formed
preferably of wire bent in a suitable man-
ner. 60

The wringing device comprises a crank
handle 6 journaled in the lower part of the
handle 1 and having a loop or yoke shaped
mop-cloth receiving hook 5 at its rear end
and an operating handle 20 at its opposite 65
end.

The mop cloth according to the present
invention is provided at the front end and at
the rear end with loops 8.

By means of said loops the rear end is 70
connected to the hook 5 of the wringing de-
vice and the front end to the hook 10 illus-
trated in Figure 2 and consisting of two
spaced and U-shaped limbs 21 forming at
one end an eye 23 and leaving at the other 75
end a slot 22 between them for inserting the
loops 8.

In this manner the mop cloth 7 is con-
nected to the hooks 5 and 10 in such a way,
that although it cannot become unfastened, 80
it may easily be removed and turned either
upside down or end-for-end for obtaining
an equal wear and tear.

During the mopping of the floor the mop
cloth 7 connected to the hook 5 and pro- 85
vided with the hook 10 is kept stretched by
the frame 4 pressing upon it and by the
hook 10 being placed upon the knob 20 of
the crank handle 6, as illustrated in Fig-
ure 1. 90

After mopping the floor the hook 10 is
removed from the knob 20 and by raising
the frame, for example by bringing the han-
dle 1 to a horizontal position the mop cloth
7 is made to hang down from the hook 5. 95

In this position the apparatus with the
mop cloth hanging down from the wringing
device is brought above the bucket and the
mop cloth is washed out in the water con-
tained in said bucket by moving the han- 100
dle 1 up and down after lowering the same
until it is submerged.

Subsequently to the washing the wringing
takes place.

In order to achieve this operation the 105
hook 10 is made to engage the handle of the
bucket and then the handle 1 is raised until
the mop cloth is stretched and the handle

of the bucket is brought to a vertical position in which position the mop cloth is just above the centre of the bucket. The mop cloth is then wrung out by turning the crank handle 6, whereby the water freed therefrom drops into the bucket.

Due to the loops 8 provided at the ends of the mop cloth 7, the same is wrung out over its whole length and a uniformly dried mop cloth is obtained.

All the operations mentioned above can be executed without manually handling the mop cloth, but it is necessary to lift the handle of the bucket in order to enable the hook 10 to engage the same while at the same time maintaining the mop above the bucket.

This lifting of the bucket-handle can be avoided in the manner illustrated in Figure 4, in which the loops 8 engage a ring 9 and in which, instead of the hook 10, a hook 11 is used, said hook 11 being provided with a boss 14 pivotally mounted on the wooden grip 16 which is generally arranged on the middle of the bucket-handle 12, and provided with a cam 15 arranged in such a manner as to hold the hook 11 in an upwardly directed and inclined position when the handle 12 is resting upon the upper edge of the bucket 13.

What I claim is:

1. A mop comprising a plate, a frame carried thereby, a mop handle carrying said plate, a crank journaled in and extending through said handle and a mop-cloth con-

nected at its opposite ends to the opposite ends of said crank and extending across said frame.

2. A mop comprising a plate, a frame carried thereby, a handle pivotally connected to said plate, a crank journaled in said handle and provided with a loop at one end and an operating knob at the opposite end, a mop cloth connected at one end to said loop and extending across said frame, and means for detachably connecting the opposite end of said mop cloth to said knob.

3. A mop comprising a plate, a frame carried thereby, a mop handle carrying said plate, a mop wringing device carried by said handle and provided with an operating knob at one end, a mop cloth connected at one end to said wringing device and a hook removably connected to the opposite end of said mop cloth and adapted to be engaged to extend the mop cloth during the wringing operation, said hook being provided with an enlargement adapted to receive and engage the aforesaid knob to retain the mop cloth in extended relation over said frame during the mopping.

In testimony whereof, I have signed my name to this specification in the presence of two subscribing witnesses.

PIETER DULLAARDT.
